UNITED STATES PATENT OFFICE.

OTTO SCHIMANSKY, OF OAK HARBOR, OHIO.

WAGON-STANDARD.

SPECIFICATION forming part of Letters Patent No. 286,335, dated October 9, 1883.

Application filed June 28, 1883. (No model.)

To all whom it may concern:

Be it known that I, OTTO SCHIMANSKY, of Oak Harbor, Ottawa county, Ohio, have invented certain Improvements in Wagon-Bolsters, of which the following is a specification.

5 My invention is a bolster or wagon-stake constructed, as fully described hereinafter, so as to secure strength and rigidity with comparatively small weight, and permit ready application to bolsters or cross-bars of different dimensions.

15 In the drawings, Figure 1 is a side elevation, showing a part of a bolster and the improved stake applied thereto. Fig. 2 is an end view of Fig. 1; and Fig. 3 is a sectional plan on the line 1 2, Fig. 1.

20 A is the cast-metal portion of the stake, being a standard solid or continuous at the upper end, but divided at the lower end to form two legs, *a a'*, the former being angular or T-shaped in cross-section to secure stiffness with little weight, and the latter extending outward at a slight angle to constitute a brace. At the lower end of the legs are perforated lugs *c*, 25 through which to pass vertical bolts *e*, for securing the stake to the bolster.

25 B B are the side bars of the stake, each consisting of a rod of malleable metal, bolted at the upper end to the side of the standard, extending outward at a slight angle and projecting below the lower ends of the legs *a a'*, and perforated to receive a cross-bolt, *b*. These

bars B not only impart vertical stiffness, but also brace the stake, so as to sustain it against side-thrusts, which would tilt it, and thereby 35 loosen the bolts *e* or break off the lugs *c*. When the stake is large and heavy, two or more brace-bars, B, may be secured at each side, and in some cases the standard may be cast solid throughout.

40 I claim—

1. A wagon-stake consisting of a solid standard, A, forked at its lower end, secured to the bolster by vertical bolts *e*, and independent side bars, B B, secured at their upper ends on opposite sides of the standard and projecting below the lower end thereof, and connected to the bolster by a cross-bolt, *b*, substantially as set forth.

2. The wagon-stake consisting of the solid standard A divided at its lower end to form two legs, *a a'*, bolted to the top of the bolster, and independent side rods, B B, connected on opposite sides of the standard and by a cross-bolt to the sides of the bolster, substantially 55 as set forth.

In testimony whereof I have signed my name to this specification in the presence of two subscribing witnesses.

OTTO SCHIMANSKY.
